US0D1091699S

(12) **United States Design Patent** (10) Patent No.: **US D1,091,699 S**
(45) Date of Patent: ** Sep. 2, 2025

(54) **ELECTRONIC SHELF LABEL**

(71) Applicant: **Hanshow Technology Co., Ltd.**,
Jiaxing (CN)
(72) Inventors: **Peixuan Liu**, Zhejiang (CN); **Linjiang Wang**, Zhejiang (CN); **Xubing Du**, Zhejiang (CN); **Shiguo Hou**, Zhejiang (CN); **Jianguo Zhao**, Zhejiang (CN); **Ming Shen**, Zhejiang (CN)

(**) Term: **15 Years**

(21) Appl. No.: **35/524,288**

(22) Filed: **Feb. 14, 2025**

(80) **Hague Agreement Data**

Int. Filing Date: **Feb. 14, 2025**

Int. Reg. No.: **DM/244685**

Int. Reg. Date: **Feb. 14, 2025**

Int. Reg. Pub. Date: **Mar. 14, 2025**

(30) **Foreign Application Priority Data**

Primary Examiner — Catherine Ho

(57) **CLAIM**

The ornamental design for an electronic shelf label as shown and described.

DESCRIPTION

3. Electronic shelf label

3.1 Perspective

3.2 Front

3.3 Back

3.4 Left

3.5 Right

3.6 Top

3.7 Bottom

Purpose of the design product: The intended use of the electronic shelf label is for displaying information such as product name and price.

1 Claim, 7 Drawing Sheets
